JOHN T. WILSON, OF ALAMEDA, CALIFORNIA.

COMBINED PISTON AND PACKING-RING.

1,380,454.

Specification of Letters Patent. Patented June 7, 1921.

Application filed April 7, 1919. Serial No. 288,040.

To all whom it may concern:

Be it known that I, JOHN T. WILSON, a citizen of the United States, residing at Alameda, in the county of Alameda and 5 State of California, have invented certain new and useful Improvements in Combined Pistons and Packing-Rings; and I do hereby declare the following to be a full, clear, and exact description of the invention, such 10 as will enable others skilled in the art to which it appertains to make and use the same.

A gas engine piston usually consists of an integral cylindrical casting provided with 15 circumferential grooves in its exterior surface to receive packing rings which frictionally bear against the interior surface of the cylinder to form tight joints therewith during all periods of the reciprocating 20 motions of the piston.

The front end of the piston and the packing rings which project slightly beyond the exterior surface of the piston are subjected to great pressure by the generated energy of 25 the explosive charge. The packing rings necessarily are of small cross sectional area and cut apart so they can be sprung over the end of the piston into the grooves. Being of small dimensions, they soon wear out 30 and the piston body then frictionally engages the interior surface of the cylinder and wears away the metal of the cylinder and opens a passageway for the gases generated by the explosion. Also the ends of 35 the rings frequently break and become displaced so the gases can pass. Under the same conditions when explosive charges are drawn into the explosion chamber, a vacuum being formed therein, lubricating oil from 40 the crank chamber is sucked past the packing rings into the explosion chamber, where it becomes carbonized and fouls the cylinder and piston.

These conditions obviously impair the efficiency of the engine, and the remedy therefor does not consist simply in using wider packing rings, for the wider the ring, the greater the pressure beneath it and the greater the friction between the ring and 45 the cylinder.

The object of the present invention is to cure these imperfections by providing a packing ring, of a shape conforming to the shape of the groove in the piston, and presenting a relatively large area of exterior 50 wearing surface and a much less area of

surface at the interior to be acted upon by the pressure of the explosive gases and the pressure of the explosive charge when being compressed—that is, to exclude from part of 60 the interior surface of the ring the pressure due to the compression of the charge and also the explosion of the charge; but when the charge is drawn in by suction, a vacuum being formed in the explosion chamber, permitting air at atmospheric pressure containing more or less of lubricating oil, it passes beneath the entire under surface of the packing. 65

The invention consists in a single cut 70 resilient expandible packing ring and a piston having a groove of a shape in conformity with the shape of the ring whereby the results above set forth are attained.

Further, the invention consists in certain 75 novelties of construction and relative arrangements, as herein set forth, of the ring, the groove in the piston adapted to receive the ring, and the crank and explosion chambers. 80

The accompanying drawing illustrates an example of the embodiment of the invention constructed and the parts combined according to the best of the several modes of procedure I have so far devised for the 85 attainment of the ends set forth.

Figure 1 is a vertical section in elevation of a gas engine piston and cylinder showing my invention, several packing rings being shown in section. 90

Fig. 2 shows the face of a ring adjacent the explosion pressure end of the piston.

Fig. 3 is the opposite face view of Fig. 2.

Fig. 4 is a top plan view of Fig. 2.

Fig. 5 is an enlarged view of the joint 95 member in perspective.

Fig. 6 illustrates the position of the packing ring in the groove when the charge is being drawn into the explosion chamber.

Fig. 7 illustrates the position of the ring 100 when the charge is being compressed and also when the explosion is taking place in the chamber.

Referring to the figures, the letter A designates a solid piston of well known general shape and construction, exclusive of the shape of the grooves in its exterior surface. The lines B—B and shading lines represent part of the interior circular surface of the engine cylinder presenting a smooth 110 surface throughout, and part of the metal of the cylinder. C is the end of the piston

forming the movable inclosing boundary of the explosion chamber D, and E is the end of the piston facing the inclosed crank chamber space F which contains a heavy 5 lubricating oil or other lubricant. G designates the grooves in the exterior surface of the metallic body of the piston. R are the packing rings.

Referring to a single combined groove 10 and ring, it will be noted that each is adapted to the shape of the other. The outer part of the groove 1 is of the same width throughout the circumference of the piston. Its depth at 2 adjacent the end of the piston 15 next to the explosion chamber is greater than its depth at 3 adjacent the crank chamber end of the piston. In other words, the groove is of a general L-shape and the vertical surfaces defining the same are plain to 20 match the surfaces at the sides of the packing ring.

The ring R is shaped to loosely fit the groove, its exterior portion being wider than its interior portion, and of a general L-shape 25 in cross section. The part 4 may be called a flange and in the groove it is remote from the explosion chamber and faces the crank chamber. The ring may project slightly from the groove to engage the interior surface 30 of the cylinder and there should be a slight space as indicated between the side and bottom surfaces and the metal surfaces defining the groove so the ring can "float" longitudinally relative to the axis of the piston and also at right angles thereto so as 35 to frictionally engage the interior surface of the cylinder throughout.

The ring is in a single piece, except the joint plate, and of resilient expandible metal. 40 It is cut or severed so it can be sprung over the end of the piston. A tight joint must be provided at the cut ends of the ring and in this instance it is formed as shown by the drawing.

Tongues 5, 5 are fashioned at the ends of the ring, and a joint member or piece fashioned to match them and the ends of the ring. The joint member has two recesses 6, 6 which may merge into a single slot to receive the tongues, a flange 7, and a bottom plate 8. The parts of the ring to exclude explosion pressure to and beneath the flanged part of the ring are the bottom plate 8 and the part of the joint member designated by 9 55 fitting the vertical surface of the ring on the side thereof adjacent the explosion pressure end of the piston and the explosion chamber.

It should be noted here that in gas engine practice, unlike that when steam is the 60 motive power, the packing ring must loosely fit the groove in the piston so that when the ring and groove become fouled by the products of incomplete combustion of the charge, which is always the case more or less, the 65 ring will not stick in the groove. That is,

the ring should have some slight side play within the groove so it will not pack and be prevented from expanding against the interior surface of the cylinder.

The ring in the operation of the engine is 70 subjected to three varying pressures.

First, when the charge is drawn in, a vacuum being formed in the explosion chamber, air and oil at atmospheric pressure, at 15 75 pounds to the square inch or less, pass to the entire under surface of the ring which does not excessively force the ring against the interior surface of the cylinder, but sufficiently to prevent the passage of oil beyond the ring to the explosion chamber. The 80 pressure against the entire under surface of the ring is not sufficient to cause excessive friction and wear of the ring, so a wide ring may be employed under these conditions. The ring occupies the position shown in Fig. 85 6, the surfaces of the ring and groove at a being in frictional contact so as to form a tight joint against the passage of air or oil.

Secondly, when the charge is being compressed the ring shifts to the position shown 90 in Fig. 7, the mixture under compression passing to the space b beneath only part of the under surface of the ring, the surfaces of the ring and groove at c forming a tight joint so the pressure cannot reach the under 95 surface of the ring flange.

Thirdly, when the explosion of the charge is taking place the ring under very great pressure maintains its position shown in Fig. 7 and excludes pressure from the under 100 surface of the flange of the ring.

Under the last two conditions enumerated the pressure under part of the ring is sufficient to force the ring into frictional contact with the interior surface of the cylinder and maintain a tight joint therewith so a much wider ring can be used without occasioning excessive wear thereof or wear of the interior surface of the cylinder. 105

It is clear that a piston and ring combined 110 and operating as herein described attain very desirable results. A relatively large bearing surface is secured so the ring will wear much longer than a narrower ring which is liable to break, and the ring is not 115 forced against the interior surface of the cylinder by great or excessive pressure during the explosion of the charge, for the greatest pressure, due to the explosion of the charge, is excluded from part of the under 120 surface of the ring. It is also clear that oil from the crank chamber cannot pass the ring when a vacuum is caused in the explosion chamber for drawing in the explosive charge.

125 What I claim is:

The combination with a cylinder and a piston having a circumferential groove wider adjacent the exterior surface of the piston than at the bottom, the greatest depth 130

of said groove being adjacent the explosion chamber, of a single cut resilient expansible flanged packing ring of a shape in cross section matching and loosely fitting the groove 5 and its entire exterior surface frictionally engaging the interior surface of the cylinder, and a joint member excluding explosion and charge compression pressure from the flanged portion of the ring, but admitting 10 atmospheric pressure to the entire under

surface of the ring while the explosive charge is being drawn into the explosion chamber, said groove in the piston when the packing ring is in place being entirely closed as far as possible to the entrance of gas 15 under pressure to the space beneath the packing ring.

In testimony whereof I affix my signature.

JOHN T. WILSON.
